UNITED STATES PATENT OFFICE.

WALTER T. GORDON, OF JUNIPER, OREGON, ASSIGNOR OF ONE-HALF TO
WALTER G. MOORE, OF CHICAGO, ILLINOIS.

COIN-SAFE.

No. 836,318.

Specification of Letters Patent.

Patented Nov. 20, 1906.

Application filed February 5, 1906. Serial No. 299,544.

To all whom it may concern:

Be it known that I, WALTER T. GORDON, a citizen of the United States, and a resident of Juniper, in the county of Umatilla and State of Oregon, have invented certain new and useful Improvements in Coin-Safes; and I do hereby declare that the following is a full, clear, and exact description thereof, reference being had to the accompanying drawings, and to the letters of reference marked thereon, which form a part of this specification.

This invention relates to a novel coin-safe of that class designed to receive and hold coins and commonly known as "portable saving-banks."

My improvements are designed more specifically for embodiment in that class of coin-safes which are given out by banking institutions to their customers and when filled or partially filled are returned to the banking institution, the safe opened, and the coins therein withdrawn for the purpose of depositing the same in the bank. The said safes are given out by the banking institution closed and locked by means not readily opened by the customer, so as to insure that the safes will be returned to the bank for opening in the ordinary use of the same. While adapted to the purpose described, a safe embodying my invention may also be employed as an individual safe for private use.

The object of my invention is to simplify the construction of such safes, to economize in the cost of their production, to simplify the operation of opening and closing them, and to provide a safe that is exceedingly convenient to handle and carry.

The safe herein shown, embodying my invention, comprises a casing embracing two separable cup-shaped members adapted to be brought together at their margins to inclose the coin-receiving chamber and provided with marginal interlocking devices so constructed as to be readily separable, while effectively holding the side members from separation, and said temporary fastening devices are combined with means for sealing or permanently fastening said members together, which locking means are capable of being released only by a special instrument or tool provided for the same. The locking means herein shown consists of a tubular

rivet that extends through registering apertures in the two members or parts attached thereto.

As shown in the drawings, Figure 1 is a side elevation of a safe made in accordance with my invention. Figs. 2 and 3 are side elevations of the two members of the safe. Fig. 4 is an edge view thereof. Fig. 5 illustrates the locking-lug for locking the two parts of the safe together. Fig. 6 illustrates the same parts slightly separated. Fig. 7 is a detail illustrating a spring-guard for preventing the removal of the coins through the coin-receiving slot. Fig. 8 illustrates one form of device for locking the parts together or sealing the same. Fig. 9 is a side elevation, partially broken away, of the safe, showing another mode of fastening the members thereof together. Fig. 10 is a section taken on line 10 of Fig. 9. Fig. 11 is a side view, partially broken away, showing another form of safe. Fig. 12 is an edge elevation thereof. Fig. 13 is an axial section. Figs. 14 and 15 are inner face views of the two members of the safe shown in Fig. 11. Fig. 16 is a detail section taken through the telescopic members of the safe, showing the manner of locking the same. Figs. 17 and 18 are fragmentary views illustrating the coacting interlocking connections of the two members of the casing. Fig. 19 is a detail section illustrating the spring-guard for preventing the removal of the coins through the coin-receiving slot.

The safe shown in Fig. 1 comprises two side members A and B, made concave or cup-shaped and adapted to meet at their margins with their concave sides facing each other to form the coin-receiving chamber. A slot C is provided, located, as shown in Fig. 4, at the edge of the case, to receive the coins. The said members A and B are provided at their margins with inwardly-turned lugs a b, and the lugs of one member are designed to interlock with the lugs of the other member to hold the members from separation. Such interlocking of the marginal lugs of the members may be effected in any suitable manner. As herein shown, the interlocking connections are such that the members are locked together and released by relative rotation of said members. For this purpose said lugs are slotted inwardly from their ends, as shown at a' b', and the parts a² b² of said lugs radially inside the slits are turned outwardly be-

yond the planes of the margins of said members, as most clearly shown in Fig. 6. In this manner the advance ends of said lugs, considered with respect to the direction of rotation of the lugs when brought together in interlocking relation, are out of line with each other, as shown in said Fig. 6, so that the slotted ends of the lugs readily pass into their interlocking positions, as best shown in Fig. 6. 10 Relative rotation of said parts, therefore, interlocks or releases said members.

The means for permanently sealing or locking the members together consist, as shown in Figs. 1 to 4 and Fig. 8, of a rivet D, Fig. 8, 15 made hollow and provided at one end with a head d, and said rivet is inserted through registering apertures a^3 b^3 of lugs A' B', extending radially outwardly, respectively, from the members A and B. The said lugs or ears 20 A' B' fit together when the marginal lugs of the members are interlocked to form a stem or handle by which the device may be handled. When said members are placed together at their margins and before they are 25 rotated to interlock the marginal lugs thereof, the lugs or ears A' B' are separated angularly, as indicated by the full and dotted lines in Fig. 1.

The rivet D when made hollow affords 30 when the safe is sealed thereby in the manner described an opening by which the safe may be suspended or may be attached to a watch-chain or the like. It will be observed that the configuration of the assembled safe is 35 generally like that of a watch; and said safe may be conveniently carried in the pocket as a watch. The said rivet D is adapted to be upset by the use of a special tool to lock the lugs A' B' of the members of the casing together and is cut away or removed by means 40 of another suitable tool or instrument. When the safe is used by the depositors of a banking institution, said safe is sealed when it is first given out to the depositor by the clerk 45 having the same in charge, and the seal is broken, so as to open the bank, when the safe is returned filled, by the receiving teller or other person. But a single set of opening and closing instruments is required by each receiving teller for any number of safes which 50 may be presented to him for deposit of the contents thereof. Said opening and closing instruments may conveniently have the form of an ordinary ticket-punch, being provided with suitable cutting or upsetting dies, as required.

A spring-guard E is provided, which is located beneath the coin-receiving slot C in such manner as to permit the insertion of a coin, 60 while preventing its removal through said slot. The guard is made of thin spring metal and, as herein shown, is attached at one end to the inner face of the member B. It is slotted laterally just inside its point of 65 attachment and turned obliquely outwardly

from the face of the member to which it is attached, so as to bring it obliquely beneath the slot C, as shown in Fig. 7. The spring is made light, so that the coin may pass readily between the inner edge thereof and the member to which it is attached; but the oblique position of the spring prevents the coins passing outwardly through the slot. 75

An advantage of the construction of the marginal fastening devices shown in Figs. 1 to 6, inclusive, is that the two members of the case may be made exact duplicates, thereby greatly economizing the cost of producing the same. 75

In Figs. 9 and 10 I have shown a modified 80 form of the means for fastening or sealing the members of the casing. As shown in these figures, but one of the members—the member A, as shown—is provided with an inwardly-directed lug A², that fits flat against the inner 85 curved face of the member B, and said lug A² and side member B are provided with registering apertures adapted to receive a fastening-rivet D, as shown more clearly in Fig. 10. In this form of the device the member A of 90 the case is provided with an enlarged opening a³, through which a part of the device for upsetting the rivet or removing same may be inserted when the safe is to be sealed or opened. 95

The form of safe shown in Figs. 11 to 19, both inclusive, comprises two side members F and G, which are provided at their margins with annular rims f g, which fit together in overlapping relation when the side members 100 of the case are brought together. The said side members are formed to provide between the sides of the casing and the rims thereof hollow beads f' g', as clearly shown in Figs. 17 and 18. One of the members—the member G as herein shown—is provided in its rim 105 with a plurality of outwardly-offset portions g², thereby producing on its inner surface a plurality of recesses g³, which extend from the margin of the rim g to the annular groove or space g⁴, inclosed by the hollow bead g', referred to. The rim f of the other member is provided at its margin with a like number of outwardly-turned lugs f², which are adapted 110 when the members are brought together to 115 pass through the recesses g³ into the annular space or groove g⁴. When said members are thus brought together, they are rotated relatively to each other, so as to move said lugs angularly out of line with the recesses, and 120 thereby lock the members from lateral separation. Such locked positions of the members are indicated in Fig. 16. This form of safe is also provided with radially-extending lugs F' G', which fit together when the 125 marginal locking devices are interlocked to form a stem or handle, and said lugs F' G' are adapted to be locked or sealed by means of the rivet D, before referred to, extending through registering apertures f⁵ g⁵ of said 130

5 lugs. The rims *f g* are provided with slots, which are brought to register to constitute a coin-receiving slot *H*. A guard *I* is provided inside the case in position to prevent the escape of coins through the slot *H*, said guard *I* being attached to the member *F* of the case, as shown in Fig. 14.

10 In the event of the coin-safe being used as a private safe and designed to be opened by the user a form of sealing device may be employed adapted for more ready manipulation to open and close the safe. Moreover, the form of the marginal interlocking lugs and the manner of their coöperation may be 15 varied within the limits of the claims without departure from the spirit of the invention.

I claim as my invention—

1. A coin-safe provided with a coin-receiving slot and comprising two separable cup-shaped members facing with their concave sides toward each other, interlocking devices on the margins of said members for locking the same from separation, said members being provided with registering apertures, and 25 a locking device adapted to extend through said apertures.

2. A coin-safe provided with a coin-receiving slot and comprising two cup-shaped members facing with their concave sides toward each other, locking devices on the margins of said members adapted to be brought together in interlocking relation, apertured lugs extending radially outwardly from the margins of said members and fitting together 35 to form a handle or stem for the device and locking means extending through the apertures of said lugs.

3. A coin-safe provided with a coin-receiving slot and comprising two cup-shaped members adapted to be brought together 40 with their concave sides facing each other, interlocking parts on the margins of said members adapted to be locked by relative rotation of said members, and means for locking the members from rotation.

45 4. A coin-safe provided with a coin-receiving slot and comprising two cup-shaped members facing with their concave sides toward each other and provided with marginal locking devices adapted to be interlocked and 50 released by relative rotation of said members.

bers, apertured lugs extending radially from the margins of said members, and locking means extending through the apertures of said lugs. 55

5. A coin-safe provided with a coin-receiving slot and comprising two cup-shaped members facing with their concave sides toward each other and provided with marginal locking devices adapted to be interlocked and 60 released by relative rotation of said members, apertured lugs extending radially from the margins of said members, and a hollow rivet adapted to pass through the apertures of said lugs. 65

6. A coin-safe provided with a coin-receiving slot and comprising two laterally-separable cup-shaped members adapted to be brought together with their concave faces toward each other, slotted lugs on the margins 70 of said members adapted to be interlocked by relative rotation of said members, apertured lugs extending radially from the margins of said members and fitted together to form a handle for the device, and a fastening device 75 extending through said registering apertures.

7. A coin-safe provided with a coin-receiving slot and comprising two laterally-separable cup-shaped members facing with their concave sides toward each other, marginal locking 80 devices for holding the members from separation, and a hollow rivet coöperating with said marginal locking devices for locking said members together.

8. A coin-safe provided with a coin-receiving slot and comprising two cup-shaped members facing with their concave sides toward each other and provided with marginal locking devices adapted to be interlocked and 85 released by relative rotation of said members, 90 apertured lugs extending radially from the margins of said members, and locking means extending through the apertures of said lugs, said members being made duplicate parts.

In testimony that I claim the foregoing as 95 my invention I affix my signature, in presence of two witnesses, this 27th day of January, A. D. 1906.

WALTER T. GORDON.
